UNITED STATES PATENT OFFICE.

ELIJAH S. CASWELL, OF TAUNTON, MASSACHUSETTS.

SHOE-NAIL.

SPECIFICATION forming part of Letters Patent No. 229,376, dated June 29, 1880.

Application filed March 5, 1880. (Model.)

To all whom it may concern:

Be it known that I, ELIJAH S. CASWELL, of Taunton, in the county of Bristol and State of Massachusetts, have invented a new and Improved Nail, of which the following is a specification.

The object of this invention is to provide a nail especially designed for the manufacture of shoes and boots.

10 The figure of the drawing is an enlarged perspective view of a nail having a beveled head and point and projecting shoulders.

Similar letters of reference indicate corresponding parts.

15 In the manufacture of boots and shoes whose soles are fixed to the uppers by nails a channel is formed around the sole a short distance from its edge, and within this channel the nails are driven, the boot or shoe being placed on 20 an iron last; hence the nails used for this purpose are called "channel-nails."

In the drawing, A represents the nail, having a beveled head, a, a central beveled point, b, and shoulders d d, projecting from its opposite sides. The shoulders d d are formed on 25 its opposite sides as it is gripped by the heading mechanism of the header.

When used as channel-nails for boots and shoes the beveled points of these nails, coming 30 in contact with the iron last, rarely or never

fail to turn upward in the direction desired, and clinch in the sole of the boot or shoe without any distortion of the shank of the nail, and the points of the nails can be so entered into the channel through the sole that they will clinch 35 to either side, as desired. With sharp tack-pointed channel-nails, on the other hand, or square-pointed nails, it is never certain in what direction the point may turn.

The beveled heads of these nails, being so 40 narrow, are easily covered by the flap made in forming the channel in the sole of the boot or shoe, so that the said sole shall present a neat and finished appearance.

These nails may be used for other purposes 45 than channel-nails, their beveled heads and points insuring strong and neat finish for whatever work they may be applied.

Having thus described my invention, I claim as new and desire to secure by Letters Patent—

As an improved article of manufacture, the shoe or boot nail A, having the oblong head a and point b, beveled equally on both sides, and the opposite shoulders d, arranged as 55 shown and described.

ELIJAH S. CASWELL.
